COMBINATION CAP AND SPREADER

John J. Williams, Wheeling, W. Va., assignor to
Hazel-Atlas Glass Co., Wheeling, W. Va., a
corporation of West Virginia

Application May 18, 1932, Serial No. 612,076
Renewed November 20, 1934

3 Claims. (Cl. 91—67.2)

This invention relates to bottle and jar closures, and has for its primary object to combine with such a cap, a brush or other spreader for the contents of the receptacle.

5 A further object of the invention consists in so constructing the cap and brush that they may be secured together without in any way disfiguring the outward appearance of the cap, and in fact produce a cap having a plain exterior 10 surface in simulation of a molded cap.

A still further object of the invention resides in providing a rigid connection between the cap and brush so that the cap itself may serve as an efficient gripping device when manipulating 15 the brush.

Other objects and advantages of the invention will be in part apparent and in part pointed out in the following description of the drawing, in which,

20 Figure 1 is a side elevational view of the unitary construction of cap and brush; and

Figure 2 is a vertical longitudinal section therethrough.

More specifically, the numeral 1 indicates generally the cap which is composed of inner and outer shells 2 and 3, respectively, each composed of a top or disc portion and a skirt. The skirt of the inner shell 2 is formed with screw threads or other bottle engaging means 4, and 30 preferably with a stiffening bead 5 at its lower edge.

The outer shell 3 is entirely plain and is provided with an inturned flange 6 on the lower edge of its skirt for engaging the bead 5 of the inner shell and firmly clamping the two shells together.

In order to provide the desired connection between the brush and cap, the inner shell 2 is provided with a centrally disposed opening 7 in its top for the reception of the upper end of the shank 8 of the brush 9. In the present embodiment of the invention the handle 8 is formed with a circular flange 10, which is seated between the tops of the two shells 2 and 3 and forms not only an interlocking connection between the cap and brush, but also a brace for the brush so as to form a rigid connection between the parts.

If desired, a centrally apertured liner 11 may be clamped between the tops of the inner and outer shells and encircling the flange 10 of the brush, thereby forming a liquid tight seal between the parts. A second liner 12, is also preferably employed in the top of the inner shell. 55 It is provided with an aperture for the reception

of the shank portion 8 of the brush and provides the necessary seal between the cap and receptacle.

In assembling the device it will be obvious that the brush is first inserted through the opening in the top of the inner shell so that the flange 10 engages the surface thereof. The liner 11 may then be placed in position and the outer shell 3 engaged over the inner shell, after which the flange 6 is bent inwardly to rigidly secure 10 all of the parts together. The liner 12, if employed, may be inserted at any time.

From the foregoing description it will be seen that I have devised a combination screw cap and brush in which the outer surface of the cap 15 is entirely free of screw threads or other structural features which might mar its appearance; that the connection between the brush and cap is liquid tight; and that the mounting of the brush in the cap is sufficiently rigid and substantial to permit the cap to be used as a handle 20 in manipulating the brush.

In accordance with the patent statutes I have described what I now believe to be the preferred form of construction but various changes and 25 modifications may be made without departing from the spirit of the invention, and all such changes and modifications are intended to be included within the scope of the appended claims.

What I claim is:

1. A combination bottle cap and spreader including an inner shell having a top and a depending skirt, container engaging means provided on the skirt, an outer shell having a top and a depending skirt, the outer shell encompassing the inner shell and turned inwardly about the inner shell to hold the two shells against relative rotation, the outer shell being smooth throughout to simulate a molded cap, 35 the top of the inner shell provided with an opening to receive the shank of the spreader, the spreader shank terminating within the shells, a flange provided at the top of the spreader shank, and said flange clamped between the tops of the 40 inner and outer shell.

2. A combination bottle cap and spreader including an inner shell having a top and a depending skirt, container engaging means provided on the skirt, an outer shell having a top and a depending skirt, the outer shell encompassing the inner shell and turned inwardly about the inner shell to hold the two shells against relative rotation, the outer shell being smooth throughout to 50 simulate a molded cap, the top of the inner shell 55

provided with an opening to receive the shank of the spreader, the spreader shank terminating within the shells, a flange provided at the top of the spreader shank, said flange clamped between the tops of the inner and outer shells, and a liner clamped between the tops of the inner and outer shells, the liner having a centrally arranged opening to receive said flange.

3. A combination bottle cap and spreader including an inner shell having a top and depending skirt, threads formed on the skirt to engage a container, an outer shell having a top and a depending skirt, the outer shell encompassing

the inner shell, the outer shell being smooth throughout to simulate a molded cap, the lower portion of the skirt of the outer shell being bent inward about the lower portion of the skirt of the inner shell to clamp the two shells together, a brush provided at the lower end of the spreader shank, the spreader shank terminating within the shells, and a flange provided at the upper end of the spreader shank, said flange being clamped between the tops of the inner and outer shells. 5

JOHN J. WILLIAMS.
